UNITED STATES PATENT OFFICE.

JOHN D. BLAGDEN AND GUSTAV A. TIENSCH, OF MEMPHIS, TENNESSEE.

STAMP-AFFIXING DEVICE.

SPECIFICATION forming part of Letters Patent No. 790,815, dated May 23, 1905.

Application filed August 15, 1903. Serial No. 169,641.

To all whom it may concern:

Be it known that we, JOHN D. BLAGDEN and GUSTAV A. TIENSCH, citizens of the United States, residing at Memphis, Shelby county, 5 State of Tennessee, have invented certain new and useful Improvements in Stamp-Affixing Devices, of which the following is a specification.

Our invention relates to certain new and useful improvements in stamp-affixing devices, and has especial reference to a device for affixing postage-stamps to letters, postals, circul 10 ars, &c., in which device a magazine containing stamps is used to hold the stamps which 15 are successively placed by the machine on the letters.

The objects of our invention are, first, to provide a simple machine in which a number of stamps can be placed and successively affixed 20 to letters; second, to provide means whereby the stamps themselves will not be moistened except as they are placed on the letter, and therefore the moisture from one stamp will not be communicated to the adjacent stamps 25 in the magazine and they will therefore not be damped and stick together.

In carrying out our invention we employ a box or receptacle for the superposed stamps, which box is removable from and may be inserted after filling in the main magazine of 30 the affixer. We also employ a moistening pad or sponge, which moistens the envelop where the stamp is to be placed and which is withdrawn by the action of the device when the 35 stamp is being pushed down against the envelop.

In the drawings, Figure 1 is a sectional elevation of our device, showing the plunger depressed and the magazine about one-half full 40 of stamps, with the stamps pressed down in the position which they take when they come against an envelop, showing also the moistening-pad pushed out to one side after having moistened the envelop. Fig. 2 is a side elevation showing the plunger-handle up and the moistening-pad in place beneath the magazine. Figs. 3 and 4 are detail views showing the magazine for the stamps removed from the main 45 magazine.

Referring now to the drawings, in which like numerals indicate the same or like parts in all the views, 1 1 are the side frames of the machine, connected at the lower end by a rod 2 and at the upper end by rods 3 and 4, forming a rigid frame. 50

5 is a guiding-slot in the frame.

6 is a plunger-chamber free to move vertically and guided in the frame of the machine by pins 7 and 8, which pins are so placed that they allow this chamber to be depressed until 60 it comes flush with the bottom of the frame 1.

In the lower end of the chamber 6 is a removable stamp-magazine 9, having pins 10 projecting inward and (see especially views 3 and 4) supporting the stamps, as will be more 65 fully hereinafter explained.

Mounted in the plunger-chamber 6 and so constructed as to pass the magazine 9 is a plunger 11, which is carried on a stem 12, which projects upward through a circular 70 opening in the top of the chamber 6 and which is therefore guided by the said opening and the said plunger in the lower portion of the chamber. This plunger is held normally raised by a spring 13, surrounding the stem 75 12 and resting against the under side of the handle 14, fixed to the stem 12. The lower end of this spring rests on top of the chamber 6.

15 is a cylindrical covering to prevent the 80 hand catching in the spring when the plunger is being depressed.

16 is a frame pivoted on the rod 4 and normally held beneath the magazine 9 by a spring 17, coiled around the said rod 4. 18 is a cross-bar connecting the two sides of this frame. In the lower end of this frame is a sponge-box 19, which is mounted on a pivot 20 and is held down by a tension-spring 21 acting outside the pivot. 90

22 is a stop which comes against the frame 16 to prevent the sponge-box being thrown too far around.

23 is the sponge which moistens the envelop. This sponge is placed in the holder and its 95 upper surface is covered so that it will not moisten the stamp.

The sponge-box 19 and frame 16 are moved

outward as the plunger is depressed by the pin 8, which works against a cam 23, extending inward from said frame 16 into the path of the said pin 8. When, therefore, the pin 5 8 descends, it pushes the cam out of its path, and thereby moves the sponge to one side, drawing it across the paper.

In use the magazine 9 is removed from the plunger-chamber 6 and is filled from the top 10 with separate stamps, which rest on the pins 10. When filled, the magazine is inserted in the bottom of the plunger-chamber 6, where it may be held in any way desired, but preferably only by the friction of the magazine on the chamber. The sponge having been wet the device is ready for use. It is grasped by the handle 14 and is placed on the envelop at the point where it is desired to place a stamp. The plunger is depressed, carrying down with 15 it the plunger-chamber 6 and pushing the cam 23 to one side, so that the sponge is drawn across the face of the envelop where the stamp is to go. After the sponge-holder has been pushed to one side the plunger-chamber continues to descend until it rests on the envelop. Further pressure compresses the spring 13 and allows the plunger 11 to come down on the stamps and force them against the envelop. The lower stamp coming against the 20 moistened envelop adheres to it and when the plunger is again raised is pulled out of the bottom of the magazine, remaining on the envelop. The remaining stamps not having been touched by the moistened surface or having come in contact for even a short time with a moistened stamp are not affected and remain in the magazine without adhering together. The device may be removed to the 25 next envelop and the operation repeated. The frame 1 hangs loosely on the plunger-chamber 6 when the device is raised, and the plunger-chamber will assume very much the position shown in Fig. 1 when it is pushed down when not in use, except that the depressed 30 plunger-chamber will not be pressed down against the envelop.

Having described our invention, what we

claim, and desire to secure by Letters Patent in the United States, is—

1. In an apparatus for affixing stamps or 50 similar articles, the combination with a plunger-chamber, a plunger mounted therein, a spring normally holding said plunger raised, pins projecting from said plunger-chamber, a slotted frame mounted on said pins, a swinging frame mounted in said slotted frame, a cam projecting inward from said swinging frame into the path of one of the pins on said plunger-chamber; a sponge-holder having one end free mounted in the lower end of said swinging frame, a stop on said sponge-holder, a spring normally depressing the free end of said sponge-holder and a spring working on said swinging frame to hold said sponge-holder normally beneath said plunger-chamber, of a 55 removable stamp-magazine in said plunger-chamber, substantially as shown and described.

2. In an apparatus for affixing stamps or 60 similar articles, the combination with a plunger-chamber, a plunger mounted therein, a spring normally holding said plunger raised, pins projecting from said plunger-chamber, a slotted frame mounted on said pins, a swinging frame mounted in said slotted frame, a 65 cam projecting inward from said swinging frame into the path of one of the pins on said plunger-chamber; a sponge-holder having one end free mounted in the lower end of said swinging frame, a stop on said sponge-holder, a spring working on said swinging frame to 70 hold said sponge-holder normally beneath said plunger-chamber and the removable stamp-magazine 10, with the projecting pins 11 in the lower end of said plunger-chamber, 75 substantially as shown and described.

In testimony whereof we have signed our names to this specification in the presence of two subscribing witnesses.

JOHN D. BLAGDEN.
GUSTAV A. TIENSCH.
